BALANCED VALVE

Lawrence C. Irwin, Garden City, N. Y., assignor
to Charles J. Tagliabue Mfg. Co., Brooklyn,
N. Y., a corporation of New York

Application April 10, 1933, Serial No. 665,294

9 Claims. (Cl. 251—20)

The present invention relates to balanced control valves, and particularly to pneumatically operated valves of the type known as V-port balanced valves.

It is one of the objects of the invention to provide a valve of this kind wherein the valve-seat supporting parts within the body of the valve in the path of the fluid medium flowing through the valve are so constructed and arranged that, when such medium is of a higher or lower temperature than the atmosphere surrounding the valve, such parts are not exposed to large temperature differences and are thereby protected against distortion, so that fluid-tight engagement between the valve or valves and their seats at all times is insured.

It is a further object of the invention to simplify the construction of the valve head or disc and also of the valve body, and in particular to reduce the latter to a simple casting.

Balanced diaphragm-operated valves of the kind now in use are generally provided with a cylindrical valve head cooperating with two axially spaced seats supported on the two arms of a usually horizontally disposed U-member projecting into the interior of the body of the valve from one side of the latter, generally the inlet side. This arrangement not only produces a rather complicated casting, but exposes such U-shaped support to large differences in temperature between different portions thereof when the fluid medium controlled by the valve is much above or below the atmospheric temperature. These temperature differences arise as a result of the fact that the supported ends of the U-support are in contact or integral with the body of the valve and hence are under the heating or cooling influence, as the case may be, of the circumambient atmosphere; whereas, the inner part of the U-support is constantly in contact with the hot or cold fluid medium. The differences in temperature between the free and supported portions of the U-member produce thermal stresses which frequently are strong enough to distort and deform the seats and make them slightly oval, thereby preventing fluid-tight closing of the valve and causing leakage.

According to the present invention, the valve seat supporting structure is connected to the body or housing of the valve in such a manner that all portions of the material defining the seat or seats of the valve are substantially equally distant from such valve body and hence are at substantially the same temperature. The balancing of the valve is effected by providing three

compartments within the body of the valve arranged in series, that is, in line, one end compartment communicating with either the inlet or outlet of the valve and being permanently connected with the other end compartment, while the middle compartment communicates with either the outlet or the inlet. In the preferred embodiment of the invention, as applied to a balanced valve, wherein two seats are provided for the valve head or cylinder, one of the seats is arranged within a web extending approximately diagonally from the inlet side of the valve body to the outlet side thereof, while the other seat is arranged within a flange forming part of cylindrical extension of the valve body. The fluid medium is afforded permanent access to the space within such cylindrical extension through the hollow interior of the valve head itself, so that substantially equal total pressures are exerted upon the valve head in opposite directions and the valve can be actuated by a diaphragm of small dimensions. The valve seats are preferably symmetrically positioned on axial alignment within the valve body, and are connected with the valve body by metal structure of approximately uniform radius or length, so that the rate of heating and of cooling of all parts of each valve seat is substantially the same.

Other features and advantages of the invention will appear from the following description and the elements of novelty will be set forth in the appended claims.

My invention will be described in greater detail in connection with the accompanying drawings which illustrate by way of example several embodiments of the invention. In said drawings,

Fig. 1 is a view in elevation partly in section showing a diaphragm-operated valve constructed in accordance with the invention;

Fig. 2 is a partial vertical section of the valve shown in Fig. 1 on an enlarged scale, the valve being a reverse acting valve, that is, when pressure is applied to the diaphragm thereof the valve opens;

Figs. 3 and 4 are horizontal sections along the lines 3—3 and 4—4, respectively, of Fig. 2;

Fig. 5 is a central section through a modified form of the invention, the same comprising a direct acting valve, that is, one in which upon the application of pressure to the diaphragm of such valve, the valve closes;

Fig. 6 shows another modification of the invention, the same representing a reverse acting valve, and

Fig. 7 is a view of a valve constructed similarly

to that shown in Fig. 6 but illustrating a direct acting valve.

The valve illustrated in Fig. 1 is of the dia-phragm operated type and comprises a valve body 5 or housing 10 through whose bonnet 11 extends a valve stem 12 which is connected with a plate 13 acted upon by the diaphragm 14. The plate 13 and the stem 12 are constantly urged upwardly by the spring 15. The diaphragm 14 is clamped 10 between the spider support 16 and the imperforate, arched plate 17, and is adapted to be subjected to air under pressure admitted through a pipe 18 into the space between the plate and dia-phragm. The pipe 18 is connected with a source 15 of compressed air and is controlled in any suitable manner. Upon the admission of air into the space above the diaphragm 14, the latter is depressed and the valve head within the body 10 is thereupon moved toward or from its closed position, depending upon whether the valve is of the direct or reverse acting type.

In the embodiment of the invention illustrated in Fig. 2, the valve stem 12 is connected with a cylindrical valve head 19 which is provided upon 25 its outer surface with axially spaced tapered shoulders 20 and 21. These shoulders are arranged to cooperate with two axially spaced valve seats 22 and 23 to control the communication between the inlet side 24 and the outlet side 25 of 30 the valve body. The valve seat 22 is arranged within a web member 26 extending approximately diagonally across the interior of the valve body from the inlet side to the outlet side thereof, very much in the manner of the seat-supporting web 35 of a globe valve, as will be clear from Figs. 2 and 3, the web member dividing the interior of the valve body into two compartments which have access to each other only through the seat 22.

The seat 23 is positioned within an annular member 27 which forms part of a more or less cylindrical extension of the valve body, the member 27 being screwed upon the valve body. The interior of the extension is closed by means of a cap 28 which is in threaded connection with the member 27.

The valve head 19 is hollow and in the embodiment illustrated is in permanent communication through a plurality of ports 29 with the inlet side 24 of the valve body. The ports 29 terminate 50 just above the shoulder 20, so that when the valve is in the closed position shown in Fig. 2, the inlet side 24 is cut off from communication with the outlet side 25. The steam, water or other fluid medium fed by the valve is, however, permitted to flow through the ports 29 into the interior of the hollow valve head 19 and thence through passageways 29a into the space 30 below the valve seat 23. The fluid medium has 55 access to the top of the valve head through the clearance between such head and the bonnet 11. The valve head is thus subjected to the pressure of the fluid medium at both ends thereof so that, the total pressures in opposite directions on the valve head being practically equal, the valve is 60 in substantially balanced condition and only a comparatively small pressure on the diaphragm is required to move the valve against the tension of the spring 15.

Upon depression of the diaphragm 14 by the 70 compressed air admitted through pipe 18, the valve head 19 is lowered, and when the lowermost ends of the ports 29 pass below the seat 22, communication is established between the inlet and outlet ends of the valve body. The lowermost 75 ends of the ports are preferably tapered or V-

shaped as shown to facilitate throttling of the valve.

The construction shown in Fig. 5 is similar to that shown in Fig. 2 and similar parts have been designated with the same reference characters. The arrangement in Fig. 5, however, is such that upon depression of the valve stem 12, the valve head 19 is moved toward its closed position, the valve therefore being of the direct acting type.

It will be noted that the bonnet of the valve shown in Fig. 5 is similar in construction to the parts 27 and 28 of Fig. 2, and has therefore been designated by the reference characters 27a and 28a, while the cap 11a of Fig. 5 is similar in construction to the bonnet 11 of Fig. 2; that is, the externally threaded portions of these parts are of the same size and will fit the same internally threaded connections on the valve bodies. By such design, the cap member of the one construction may be interchanged with the bonnet member 10 of the other construction, and vice versa, so that by interchanging one part for the other, a reverse acting valve may be converted into a direct acting valve and vice versa. The cylindrical valve heads 19 are provided with internally threaded 15 sockets 31 at the opposite ends thereof adapted to receive the headed end of the stem 12 which is held in position by the nut 32. It will be clear that to convert, say, the direct acting valve of Fig. 5 into a reverse acting valve, it is necessary 20 only to disassemble the valve body from the framework 16 and the stem 12, invert the body, replace the cap 11a with a bonnet similar to the bonnet 11 of the valve of Fig. 2, and replace the element 28a with the cap member 28, the valve 25 stem being positioned in the opposite socket 31 of the valve head. In this way, the operation of a valve can be reversed with the aid of standard, stock parts. If desired, the parts may be so designed that the threaded portion of the member 30 40 45 50 55 60 65 70 75 80 85 90 95 100 105 110 115 120 125 130 135 140 145 150 155 160 165 170 175 180 185 190 195 drawings, the valve bonnets are provided with shoulders 39 upon which rests the spider frame work 16 of the valve. The bonnets are provided with reduced threaded extensions 40 which pass 5 through suitable apertures in the frame 16 and receive a clamping nut 41. The valve stem 12 passes through a bore in the bonnet and is guided within the extension 40 and passes through a stuffing box 42 which serves to seal the space 10 about the stem 12 within the bonnet. Any suitable lubricating device 43 may be provided to insure easy movement of the stem 12.

Both the valve bodies and valve heads forming parts of my improved construction are characterized by extreme simplicity. The valve body of Figs. 2 and 5, moreover, can be used for both direct and reverse acting valves, while the valve heads in all of the illustrated embodiments can be used in either a direct or reverse acting valve, 20 so that the two valves require a minimum of different parts for their manufacture.

It will be noted that in all of the embodiments of the invention illustrated, the interior of the valve body is divided into three compartments, 25 the valve head or cylinder having its ends in the two end compartments and passing through the middle compartment, the two end compartments being in permanent communication so that 30 equal unit pressures are exerted upon the ends of the valve head.

It will be understood that various modifications of the form and arrangement of parts may be resorted to within the scope of the appended 35 claims without departing from the spirit of the invention.

I claim:

1. In a valve structure, the combination of a valve body, an approximately diagonal web in the interior of said body separating the inlet and 40 outlet ends thereof, said web having a port through which communication between the inlet and outlet ends of the valve body may be established, and being provided with a valve seat about said port, a hollow valve head adapted 45 to cooperate with said seat to control said port and extending at one end into the space at one side of the web and being subjected to the pressure at such side, means defining a compartment in communication through said valve head with 50 said space and sealed, when the valve head is in the closed position, from the space upon the other side of the web, the other end of said valve head extending into said compartment and being subjected to the pressure therein, said valve head 55 being provided with a port in the portion thereof extending into the first-mentioned space when the valve head is in the closed position, such port being then out of communication with the second-mentioned space and being movable into 60 communication with the latter to connect the two spaces when the valve head is moved into the open position in the direction from the first space to the second space, and means for moving said valve head.

65 2. A valve structure as defined in claim 1, wherein said valve head is of cylindrical form, axially spaced shoulders are on said valve head, a valve seat is at the entrance of said compartment, and said shoulders are adapted to cooperate with said seats, in the closed position of the valve head, to seal said compartment from the space at one side of the web.

70 3. In a valve structure, the combination of a valve body adapted to be connected to lead in and lead off pipes at its inlet and outlet ends, a web in

said valve body extending approximately diagonally across the interior thereof and separating the inlet from the outlet end, said web provided with a central opening and with a valve seat about said opening, a second valve seat in axial registry with said first-mentioned valve seat, means defining a compartment to the interior of which said second valve seat provides the only access, and a hollow cylindrical valve head passing through said central opening, and through 10 the port defined by said second valve seat and provided with closure means for cooperating with both of said valve seats for closing the ports controlled thereby when the valve is in one of its limiting positions, said valve seats facing said 15 compartment and the closure means for the first valve seat being positioned on the valve head upon the side of the web adjacent to the said compartment, said valve head extending beyond the said central opening in a direction opposite 20 to the second valve seat and provided with a port in the cylindrical wall of said extending portion which is positioned wholly at one side of the web when the valve head is in closed position and permanently connecting the space at such side 25 of said web with the interior of said compartment, whereby the opposite ends of said valve are subjected to the same unit pressures, said port upon movement of the valve head in the opening direction being brought into communication with 30 the space upon the other side of the web to connect the two spaces and cause flow of fluid from the inlet to the outlet of the valve body.

4. In a valve structure, the combination of a valve body adapted to be connected to lead in and 35 lead off pipes at its inlet and outlet ends, a web in said valve body extending approximately diagonally across the interior thereof and separating the inlet from the outlet end, said web provided with a central opening and with a valve 40 seat about said opening, a second valve seat in axial registry with said first-mentioned valve seat, a substantially cylindrical extension below said second valve seat and closed at its outer end to provide a compartment opening through said 45 second valve seat to the space at the outlet side of the web, a hollow cylindrical valve head passing through said central opening and provided with closure means cooperating with said seats to close the ports therein when the valve head is 50 in one of its limiting positions, said valve head sealing the interior of said compartment from said outlet space and provided with a port in the cylindrical side wall thereof communicating with the inlet side of the valve body and adapted when the valve is in its closed position to permit access 55 of fluid under pressure from the inlet side of the valve to the interior of said compartment to effect balancing of the valve, said valve seats facing said compartment and the closure means for the 60 first valve seat being positioned on the valve head in the outlet space and said port upon movement of the valve head in the opening direction being brought into communication with the outlet space to connect the two spaces and cause flow of 65 fluid from the inlet to the outlet of the valve body.

5. In a valve structure, the combination of a valve body, a web within said body dividing the interior of the valve body into two compartments, one of said compartments being permanently in 70 communication with the inlet end and the other with the outlet end of the valve body, said web being provided with a port substantially centrally thereof, a cylindrical valve head cooperating with 75 said port to control the flow of fluid from the

inlet to the outlet end of the body, one end of the valve head being permanently exposed to the pressure existing at one end of the valve body, and means whereby said pressure is communicated to the opposite end of the valve head so that the ends of said head are exposed to the same unit pressures, said means comprising an extension of the valve body providing a third compartment having a port controlling the access thereto and arranged in axial registry with the port in the web, said ports provided with seats facing said third compartment, and said valve head adapted to cooperate with said seats to close the same in a limiting position thereof and arranged to move into said third compartment as it is brought to the open condition, and being hollow and provided with a port in the wall thereof positioned wholly in the compartment remote from the third compartment when the valve head is in closed position and permanently connecting such compartments, said port being brought into communication with the intermediate compartment when the valve head is moved into the open position in the direction of the third compartment.

6. In a valve structure, the combination of a valve body adapted to be connected to lead in and lead off pipes at its inlet and outlet ends, a web in said valve body extending approximately diagonally across the interior thereof from one end to the other, said web provided with a central opening and with a valve seat about said opening, a hollow cylindrical valve head passing through the opening and provided with a shoulder adapted to engage said seat in a limiting position of the head, means whereby the unit pressure exerted upon the ends of the valve head are equalized, comprising an extension on said valve body providing a compartment having a port in the wall thereof opening into the space at one side of the web, said cylindrical valve head extending through said port and sealing said compartment from said space, one end of the valve head being exposed to the pressure in the space at the other side of the web, said valve head provided with a port in the cylindrical side wall thereof communicating with the space at said other side of the web and terminating short of said shoulder in such manner that when the valve head is in the closed position said last-mentioned port is out of communication with the first-mentioned space, such port constantly communicating the pressure of the second-mentioned space through the interior of the valve head to said compartment, so that the ends of the valve head are exposed to the same unit pressures.

7. In a valve structure, the combination, of a valve body, an approximately diagonal web in the interior of said body separating the inlet and outlet ends thereof, said web having a port through which communication between the inlet and outlet ends of the valve body may be established, and being provided with a valve seat about said port, a valve head adapted to cooperate with said seat to control said port and extending at one end into the space at one side of the web and being subjected to the pressure at such side, means defining a compartment in communication through said valve head with said space and sealed, when the valve head is in the closed position, from the space upon the other side of the web, the other end of said valve head extending into said compartment and being subjected to the pressure therein, and means for moving said valve head, said valve head comprising a hollow cylinder opening into the compartment and having a port in the cylindrical wall thereof permanently connecting the first-mentioned space of said valve body with the interior of the cylinder and thereby with the interior of said compartment, said port so arranged that it establishes direct communication between the interior of the cylinder and the second-mentioned space of the valve body upon opening of the valve.

8. In a valve structure, the combination of a valve body, an approximately diagonal web in the interior of said body separating the inlet and outlet ends thereof, said web having a port through which communication between the inlet and outlet ends of the valve body may be established, and being provided with a valve seat about said port, a valve head adapted to cooperate with said seat to control said port and extending at one end into the space at one side of the web and being subjected to the pressure at such side, means defining a compartment in communication through said valve head with said space and sealed, when the valve head is in the closed position, from the space upon the other side of the web, the other end of said valve head extending into said compartment and being subjected to the pressure therein, and means for moving said valve head, said valve head comprising a hollow cylinder opening into the compartment and having a port in the cylindrical wall thereof permanently connecting the first-mentioned space of said valve body with the interior of the cylinder and thereby with the interior of said compartment, said port so arranged that it establishes direct communication between the interior of the cylinder and the second-mentioned space of the valve body upon opening of the valve.

9. In a valve structure, the combination of a valve body, an approximately diagonal web in the interior of said body separating the inlet and outlet ends thereof, said web having a port through which communication between the inlet and outlet ends of the valve body may be established, and being provided with a valve seat about said port, a valve head adapted to cooperate with said seat to control said port and extending at one end into the space at one side of the web and being subjected to the pressure at such side, means defining a compartment in communication through said valve head with said space and sealed, when the valve head is in the closed position, from the space upon the other side of the web, the other end of said valve head extending into said compartment and being subjected to the pressure therein, and means for moving said valve head, said valve head comprising a hollow cylinder opening into the compartment and having a port in the cylindrical wall thereof permanently connecting the first-mentioned space of the valve body with the interior of the cylinder, said port being of V-shape and so arranged that it establishes direct communication between the interior of the cylinder and the second-mentioned space of the valve body upon opening of the valve.

10. A balanced valve comprising a housing having an inlet and an outlet, a web integral with the housing and dividing the same into two compartments which are connected respectively with the inlet and outlet of the housing, said web extending across the interior of the housing from the inlet side to the outlet side and having a port positioned centrally thereof, a hollow cylindrical valve head passing through said port and having a shoulder cooperating with the periphery thereof to control the communication between the two compartments, and means defining a third compartment and presenting a port in alignment with the first port and leading into said third compartment, said valve head extending through said second port and having a shoulder cooperating with the periphery thereof to seal the third compartment, the ends of said valve head being located in the end compartments and the intermediate portion thereof penetrating the middle compartment, said valve head having a port in the cylindrical wall thereof extending from said first shoulder in a direction opposite to that of said second shoulder and establishing permanent communication through the interior of the valve head between the two end compartments, whereby equal unit pressures are exerted on the ends of the valve head and movement thereof is facilitated, said last-mentioned port, upon opening movement of the valve head in the direction of the third compartment, being brought into communication with the intermediate compartment.

LAWRENCE C. IRWIN.
